UNITED STATES PATENT OFFICE.

JULIUS DUCKSTINE, OF NEW YORK, N. Y., ASSIGNOR TO UNDERWOOD TYPEWRITER COMPANY, OF NEW YORK, N. Y., A CORPORATION OF DELAWARE.

PRINTED PAPER WEB.

Application filed November 5, 1920. Serial No. 421,877.

This invention relates to continuous webs having a succession of printed forms thereon to be used, with interposed carbons, on a typewriting machine having a revoluble cylindrical platen and feed-rolls for advancing the webs; and an object of the invention is to overcome the ill effects of the creep of the outer ply or plies upon the inner ply or plies which takes place during line-spacing operations.

Other features and advantages will hereinafter appear.

The invention is illustrated in the accompanying drawings, in which 1 represents the inner web and 2, 3 and 4 the successive plies which lie upon the inner ply and form a composite web. For the purpose of overcoming the ill effects of the creep of the plies relatively to one another, the distance between the line-spaces 5 on the forms of the successive plies, the forms being indicated diagrammatically by transverse lines 6, is made correspondingly different from the line-space distance on the inner adjacent ply, this difference being equivalent to the amount of creep of one ply relatively to another caused by the line-feeding operation. It follows, therefore, that the length of the printed web-forms upon any outer web will be different from that on the next inner web by the amount of the creep produced for the distance each form is fed.

It is preferable to employ plies and carbon-sheets of a standard thickness, so that the respective plies of web will always lie the same distance from the platen center and the same amount of creep produced when fresh webs are used.

The variation in the length of superposed forms is calculated in accordance with the creep resulting from a fixed amount of line-spacing movement, the diameter of the platen, the extent to which the individual plies are bent around the platen when in the machine, etc. If the proper fixed amount of line-spacing is effected in connection with each set of superposed forms, the creep will be substantially that estimated, and after typing one set the next set will be properly positioned to start typing. Suitably printed webs may be used in typewriting machines either of the usual or of the fan-fold type.

Variations may be resorted to within the scope of the invention, and portions of the improvements may be used without others.

Having thus described my invention, I claim:

A set of separate continuous web-plies to be fed in superposed relation around the cylindrical platen of a typewriting machine, said plies to be typed upon simultaneously, each of said plies having a succession of printed forms upon it, the forms on each ply being of the same length, but differing in length from the forms on all of the other plies, the lengths of the forms on the different plies being proportional to the distances from the center of the platen at which the respective plies are to be fed around the platen, the arrangement being such that the excess feeding of the outside plies, instead of causing the succession of forms to creep out of register, causes the forms to creep successively into register for writing.

JULIUS DUCKSTINE.
